UNITED STATES PATENT OFFICE.

ALEXANDER BALDENWEG, OF SCHOENENWERD, SWITZERLAND, ASSIGNOR
TO C. F. BALLY SONS, OF SCHOENENWERD, SWITZERLAND.

MACHINE FOR MANUFACTURING DOWELS OR RIVETS.

SPECIFICATION forming part of Letters Patent No. 739,810, dated September 29, 1903.

Application filed March 3, 1902. Serial No. 96,504. (No model.)

To all whom it may concern:

Be it known that I, ALEXANDER BALDENWEG, a citizen of the Republic of Switzerland, and a resident of Schoenenwerd, Switzerland, have invented certain new and useful Improvements in Machines for Manufacturing Dowels or Rivets, of which the following is a specification.

This invention relates to certain new and useful improvements in machines for manufacturing dowels or rivets.

According to the invention a plain wire is operated on in such a way that after treatment it consists of a series of short sections, each comprising a central flange, disk, or head situated between two short pieces or lengths of wire, one of which is flattened out considerably, whereas the other is unflattened. These short pieces are intended to form the two ends of the dowel or rivet. The machine for effecting this operation comprises, essentially, two pairs of dies, which first come together sidewise, one pair seizing and holding the wire, while the other pair serve to produce the short flattened and unflattened lengths to constitute the ends of the dowel or rivet. The dies are also arranged to be afterward forced together endwise to cause the wire between them to spread out and produce the central flange, disk, or head. Thus at each operation one section is partly produced by the formation of a disk with a flattened piece of wire on its lower side, and the previous section is finished by the shaping of the unflattened piece of wire at its upper side. The wire is roughened or corrugated by the dies to insure its obtaining a better hold. When the sections are cut off, the flattened pieces are left of a V shape, with two separate points or fangs intended to spread apart and clench into any article in which they may be forced.

In order that the invention may be clearly understood, reference will now be made to the accompanying drawings, in which—

Figure 1 is a vertical section of the main part of the machine, showing the arrangement of the dies, the latter being apart or open. Figs. 2 and 3 are corresponding views, respectively showing the dies brought together laterally and endwise. Figs. 4 and 5

are plans corresponding to Figs. 1 and 2. Fig. 6 is a detail of the upper part of the jaws which carry the dies. Figs. 7 and 8 are inner side views of the upper and lower dies, respectively. Fig. 9 shows the lower dies as seen in plan. Figs. 10 and 11 are front and side views of a piece of wire partly finished. Figs. 12 and 13 are similar views, to a larger scale, showing more clearly the finished part and the way the sections are intended to be cut off to leave the V-shaped points. Fig. 14 shows one of the dowels or rivets thus obtained. Figs. 15 and 16 are elevations at right angles to each other, showing the general construction of the machine.

a a' and *b b'* are respectively the upper and lower pairs of dies. They are fitted in corresponding jaws *c c' d d'*, of which those on the left move laterally and those at the top move endwise or vertically. The upper jaws fit one into the other, the jaw *c* having a ledge or shoulder *c²* at each side, Fig. 6, fitting over projecting cheeks *c³* on the jaw *c'*. The lateral separation of the jaws is effected partly by springs *e*, arranged in pockets *e'* on the jaw *d'*, and the endwise separation is effected by a spring *f*, situated in a pocket *f'*. The latter movement can be limited and adjusted by a set-screw *c⁴* in the adjacent fixed part of the frame *g*. The lateral movement of the jaws *c d* toward the other jaws is effected by a crank-pin *h*, engaging a slide-block *h'*, whose end bears against the jaws. The pin is mounted on the end of a shaft *h²*, (or on a disk on said end,) which is turned or oscillated by suitable means, as hereinafter described.

The endwise or downward movement of the upper dies is produced by a hammer or pressing-block *c⁵*, which comes down at the proper time on the upper jaws *c c'*.

The wire *i* is fed forward by a pair of grooved disks *j*, operated by a ratchet *j'* and pawl *j²*, worked in any suitable manner. This feeding device, as well as the hammer *c⁵*, is only shown diagrammatically, as its construction and arrangement may be of any suitable kind, as will be readily understood. After leaving the feed-wheels the wire passes down through a central hole in the hammer *c⁵* and an upper guide or nozzle *k* to the dies, and from the latter it is led to a lower guide or

tube l . Both the guides k l are so arranged that they tend to set themselves midway between the dies, and thereby free the wire from the latter after the pressing operation. To this end the upper guide k has projections k' , which fit into pockets k^2 on the upper dies and rest against springs k^3 . The reaction of these springs both holds the guide central and also assists in separating the dies. The lower guide l is hinged to an arm l' and is acted on by a blade-spring l^2 , which is prevented from pressing it too far by a stop l^3 . Suitable recesses l^4 l^4 are provided to receive these guides when the jaws come together.

15 The upper dies a (see Fig. 7) have a roughened semicircular groove a^2 , in which the wire is held without its shape being materially altered. The lower dies have also a short groove b^2 of substantially the same shape as a^2 ; but at its upper part b^3 (see Figs. 8 and 9) this groove widens out laterally and becomes correspondingly shallower. The result is that the wire coming between the grooves a^2 and b^2 preserves substantially its original shape, 25 as seen at i^4 , Figs. 10 to 13, but that coming between the parts b^3 is flattened out, as at i^3 .

The grooves in the dies are suitably scored or roughened to produce ridges, corrugations, or notches in the parts i^2 and i^3 of the wire, 30 and so enable them to get a better hold. This roughness in the dies is not shown in some of the figures for the sake of clearness.

Referring now to Figs. 15 and 16, the parts aforesaid are mounted in a suitable frame m , 35 and the wire is fed from a reel m' , carried by a bracket m^2 , being after treatment wound upon a second reel m^3 in the lower part of the frame. The dies c c' d d' and block h' are arranged in guides n , and the plunger e^5 40 works in the head part m^4 of the frame. The upper end of the plunger is pressed upon by the lower movable jaw of a pair of spring-jaws o , which tends to force it down. It is raised by a cam or wiper p' on the cam-shaft 45 p . This shaft also carries two other cams p^2 p^3 for working the dies and the wire-feed, respectively. The die-cam works an arm h^3 on the shaft h^2 , and so gives it a rocking motion, such as required for operating the pin 50 h and slide-block h' , whereby the dies are pressed together. The cam p^3 works against a projection j^3 on a vertical sliding rod j^4 , and so raises and lowers this rod. The rod in its turn engages (by means of a pin or projection) a lever j^5 , carrying the pawl j^2 and normally drawn down by a spring j^6 . The stroke of the pawl can therefore be varied by changing the cam or by a stop set to limit the backward stroke of the lever. The cam-shaft p is 55 driven by fast and loose pulleys m^4 . The wire i is fed down through eye-holes o' in the spring-jaws o and passes down the center of the plunger e^5 .

The action is as follows: The parts being 60 in the position shown in Fig. 1, the shaft h^2 oscillates and the pin h forces the jaws c d against the jaws c' d' , Fig. 2. The upper

dies a a' thus grip the wire i , and the lower dies b b' do the same as regards their grooves b^2 ; but the part b^3 compresses its portion of 70 the wire and flattens it out in the manner above referred to, the parts i' i^2 assuming a bottle-neck outline. The wire being still tightly held in the dies, the hammer or plunger c^5 is caused to descend and forces the upper part down toward the lower pair, Fig. 3. In this movement the portion of wire between the dies is compressed in the direction of its length and caused to spread out laterally and form a head or disk i^3 , lying at right angles 80 to the wire. The crank-pin h now moves the other way, the hammer c^5 rises, and the springs e , f , and k^3 react and restore the parts to the position shown in Fig. 1. The feed-pawl j^2 is now operated and advances the wire 85 another step, and the dies coming together again, Fig. 2, produce above the last disk i^3 another short unflattened piece of wire i' , terminating in a flattened piece i^2 . Afterward the upper dies descend, Fig. 3, and produce 90 another disk, and then the parts resume their former position again, ready for the next operation, and so on.

The size of the disks or heads produced can be varied by regulating the stroke of the upper dies, which obviously depends on the height they are allowed to rise after each operation. This is readily controlled by the adjustable stop c^4 . The stroke of the feed-pawl j^2 is also adjusted to correspond at the same 100 time. It will be readily seen, Figs. 12 and 13, that when a length of wire which has been treated in this way is cut by a suitable tool, as shown in dotted lines, Fig. 12, the broad flattened parts i^2 form a double or V -shaped 105 point on one side of the disk (see Fig. 14) and the unflattened parts form a single point on the other side thereof. The dowels or double-ended rivets thus obtained are especially suitable for riveting together the inner and 110 outer soles of boots and shoes and for other like purposes. They lie entirely between the two parts or thicknesses which they unite, and thus provide an invisible joint, which is free from the objections that apply to ordinary rivets, while the central disks or heads i^3 facilitate the driving in of the rivets and also prevent them being accidentally driven in too far. Moreover, the clenching of the 115 double points and the roughening or corrugation of the sides and edges of the rivets insure a very firm and secure hold being obtained, even in very thin material.

Obviously the section of the wire i and the shape of the heads i^2 may be varied as desired.

What I claim, and desire to secure by Letters Patent of the United States, is—

1. In a machine for the production from plain wire, of wire suitable for cutting up into 130 dowels or rivets, the combination of two pairs of dies, one pair for holding and the other for shaping the wire, means for forcing said dies together both laterally and endwise, and

means for freeing the wire from the dies after each pressing operation, substantially as described.

2. In a machine for the production from plain wire of wire suitable for cutting up into dowels or rivets, the combination of two pairs of dies, means for operating said dies, upper and lower guides for the wire situated between the die-blocks, means for supporting said guides midway between the dies when the latter are open, and springs for returning them to this position after the dies have acted, substantially as described.

3. In a machine for the production from plain wire, of wire suitable for cutting up into rivets, the combination of two pairs of dies, sliding jaws for holding said dies, a slide for forcing said jaws and dies together laterally, a hammer for forcing them together endwise, feed-wheels for supplying the wire, a spring-pressed guide between the upper jaws, and a corresponding spring-pressed guide extending between the lower jaws, substantially as described.

4. In a machine for the production from plain wire, of wire suitable for cutting up into rivets, the combination of an upper pair of dies having grooves to grip and hold the wire

without altering its shape, a lower pair having grooves which are partly like those in the upper dies and partly divergent and shallow to produce broad flattened portions in the wire, means for forcing the dies together endwise to expand the wire between them and form disks or heads at right angles thereto, and means for freeing the wire from the dies after each pressing operation, substantially as described.

5. In a machine for the production from plain wire, of wire suitable for cutting up into rivets, the combination of two pairs of dies for gripping and shaping the wire, sliding jaws carrying said dies, a spring between the upper and lower jaws for forcing them apart, an adjustable stop for regulating such separation and so controlling the size of the disks or heads produced when the dies are forced together, and means for suitably forcing said dies downward.

In testimony whereof I have hereunto set my hand, in presence of two subscribing witnesses, this 15th day of February, 1902.

ALEX. BALDENWEG.
